DESIGN FOR AN AIRPLANE

John A. Kerr, Kenmore, and John A. Mattison,
Williamsville, N. Y., assignors to Curtiss-Wright
Corporation, a corporation of Delaware

Application June 6, 1944, Serial No. 113,870

Term of patent 7 years

(Cl. D71—1)

To all whom it may concern:

Be it known that we, John A. Kerr and John A. Mattison, citizens of the United States residing, respectively, in Kenmore and Williamsville, both in the county of Erie and State of New York, have invented a new, original, and ornamental Design for Airplanes, of which the following is a specification, reference being had to the accompanying drawings, forming a part thereof.

Figure 1 is a top plan view of an airplane showing my new design.

Figure 2 is a front elevational view;
Figure 3 is a side elevational view thereof, and
Figure 4 is bottom plan view.

We claim:
The ornamental design for an airplane, as shown.

JOHN A. KERR.
JOHN A. MATTISON.
